Primary Examiner—Brian N. Vinson
Attorney, Agent, or Firm—Hugh E. Smith[57] **CLAIM**

The ornamental design for a attachment to prevent the operation of a storm door closer mechanism, as shown and described.

DESCRIPTION

FIG. 1 is a front elevational view of the attachment to prevent the operation of a storm door closer mechanism showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reduced front elevational view thereof, with the broken-line disclosure of a closer mechanism and portion of a storm door being for illustrative purposes only and forming no part of the claimed design.

FIG. 1

FIG. 2
